CLAIM

The ornamental design for a trolley for medical care, as shown and described.

DESCRIPTION

FIG. 1 is a front view of a trolley for medical care;
FIG. 2 is a rear view thereof;
FIG. 3 is a right side view thereof;
FIG. 4 is a left side view thereof;
FIG. 5 is a bottom view thereof;
FIG. 6 is a top view thereof;
FIG. 7 is a first perspective view thereof with a retaining arm in a downward position;
FIG. 8 is a second perspective view thereof with the retaining arm in a lifted position; and,
FIG. 9 is a third perspective view thereof with the drip tray removed.

The broken lines immediately adjacent to the claim depict the bounds of the claimed design, while all other broken lines are directed to the environment. The broken lines form no part of the claimed design.

1 Claim, 9 Drawing Sheets
